DISH RACK SUPPORT

Louis Maslow, Dallas, Pa.

Filed Apr. 25, 1961, Ser. No. 64,897

Term of patent 14 years

(Cl. D49—1)

FIG. 1

I claim:

The ornamental design for a dish rack support, substantially as shown.
